CLAIM

The ornamental design for a home plate towel as shown and described.

DESCRIPTION

FIG. 1 is an isometric view from above a home plate towel incorporating my new design;

FIG. 2 is an isometric view from below the home plate towel of FIG. 1;

FIG. 3 is a top plan view of the home plate towel of FIG. 1; FIG. 4 is a bottom plan view of the home plate towel of FIG. 1.

FIG. 5 is a front elevation view of the home plate towel of FIG. 1;

FIG. 6 is a rear elevation view of the home plate towel of FIG. 1.

FIG. 7 is a first side elevation view of the home plate towel of FIG. 1; and

FIG. 8 is a second side elevation view of the home plate towel of FIG. 1.

The broken lines shown in the drawings represent portions of the HOME PLATE TOWEL that form no part of the claimed design.

1 Claim, 5 Drawing Sheets
